UNITED STATES PATENT OFFICE

PAUL S. JENKINS, OF DETROIT, MICHIGAN, ASSIGNOR TO SQUARE D COMPANY, OF DETROIT, MICHIGAN, A CORPORATION OF MICHIGAN

ELECTRICAL SWITCH

Application filed April 21, 1923, Serial No. 633,580. Renewed October 27, 1928.

My invention relates to electrical switches and more particularly to that class known as armour clad or safety switches wherein the switch elements, as well as other live parts of the circuit, are enclosed within a housing which is provided with a movable cover.

My invention has special reference to an interlock mechanism for controlling the position of the switch with respect to the cover, whereby the switch can not be closed while the cover is open, nor the cover opened while the switch is closed.

The present application is a continuation in part of my copending application, Serial No. 505,989, filed October 7, 1921, in so far as it involves common subject-matter. It will be later observed that the interlock, which has been illustrated in said copending application, is also illustrated herein, but with certain additions thereto, in order to increase its utility, and so that it may be universally used and standardized in switches of any size or capacity.

With the development of electric power in recent years, the use of safety switches has become quite pronounced. The advantages which are obtained from the use of these switches are numerous and at the present time need little explanation, especially in view of the disclosure in the aforesaid copending application. Some means must be provided whereby the unskilled workman may be protected from coming into contact with live circuits. In the above identified copending application, an interlock has been illustrated, which cooperates with the switch operating means, for locking the cover closed while the switch is closed, or the switch open while the cover is open. I have found this mechanism to be very efficient and satisfactory, having met with remarkable success on the market. However, its universal application to switches irrespective of capacity or size has presented a difficult problem. The difficulty has been in devising an interlock of proper size which could be aptly used on any size switch without being too weak, or too strong—or too cumbersome, for the particular switch in question. Take for example, a switch of a capacity of 200 amperes or over,

and it will be found that the inertia of the moving parts is by far greater in this switch than in a switch of less capacity. Hence it will be seen that an interlock commensurate in size to a switch under a 200 ampere capacity could not be used safely on a switch over this capacity. This is due to the following reason:

Primarily, the function of an interlock is to prevent unauthorized persons from tampering with the switch in open position when the cover is open, and to prevent them from opening the cover before the switch is opened. With reference to the first requirement, it is evident that should the cover be opened, the switch might be closed by jamming the interlock mechanism, providing the latter could be jammed. This will, of course, depend upon the size of the switch, particularly the operating member. If the moving parts of the switch are large and heavy, little trouble would be experienced in an attempt to jam the interlock mechanism. Hence an interlock mechanism of insufficient strength falls short of accomplishing the desired result, as it could not be relied upon to safeguard against the unauthorized acts of those for whom this type of switch is especially provided.

It must not be forgotten that a disabling device is contemplated, in connection with the present interlocking mechanism, in order to render the interlock ineffective, by the proper person, when desired. This disabling device has also been fully disclosed in said copending application, and has become standard equipment on safety switches provided with interlocking mechanism. To this end, the implement used to operate this disabler has been designed in the form of a standard key which may be used universally on switches of many types and sizes. The advantage of this feature is obvious when it is borne in mind that many large industrial plants use hundreds of these switches, and to require a different key for each switch would be a useless duplication and waste of material, as well as troublesome for the inspector in charge. It has, therefore, been the aim of manufacturers of switches to

standardize their interlocking mechanism, in order to permit the universal use of a single key, and thereby avoid the above objections.

Coming now to the advantages of standardizing the interlocking mechanism, as well as the disabler and key therefor, in view of what has been said, it will be observed that this can be readily accomplished if mechanism of standard size is adopted and added provision made for the larger size switches. However, should an attempt be made to provide the interlocking mechanism in various sizes considerable difficulty would be experienced. Among them would be the requirement for a heavy investment in dies and tools, and furthermore, difficulty would be encountered in designing the parts so that the standard disabling key could be used. Notwithstanding all this, the mechanism would, perforce, become more intricate, as the parts would have to be made more substantial. I have found that an attempt along this line would require the interlocking mechanism to be built in many sizes, inasmuch as one capable of being used on a switch of 200 ampere capacity would be, by far, too small for a 1200 ampere switch.

As before pointed out, according to the teachings of my invention, I provide a standard size interlocking mechanism, preferably large enough for the smaller switches. The switch cooperates with the interlocking mechanism by means of a toggle rod, or like element. When the switch is of a larger size, or of such size that sufficient force can be placed in back of the effort to close the switch while the cover is open, by jamming or permanently disabling the interlocking mechanism, I have found that the strain upon the toggle rod will cause rupturing of this mechanism or breaking of the rod.

Broadly, therefore, it is an object of my invention to reinforce this toggle rod, or connecting element, and also the interlocking mechanism. This is accomplished by the provision of a "relay connection" between the switch operating member and interlocking mechanism, so that when the cover is opened a barrier or like member may be inserted in the path of the switch operating member to prevent its movement.

A further object of my invention is to so relate the relay connection with the interlocking mechanism that it will not be necessary to change the design or construction of the latter, but on the contrary embody it, in its unitary relation, within the switch the same as in smaller capacity switches. I consider this feature important, as it allows standardization of the interlocking mechanism.

Incidental to the above advantage of employing a standard interlocking mechanism and the use of the relay connection therewith in larger capacity switches, the interlocks

thereby provided may be disabled when desired so that the switch can be closed while the cover is open. This is accomplished by the use of a disabler in conjunction with the interlocking mechanism, and inasmuch as, in the present case, I intend connecting the relay connection with the interlocking mechanism in order that it will be controlled thereby, the rendering of the interlocking mechanism ineffective will automatically render the relay connection ineffective.

Another object of my invention is to provide an improved toggle mechanism whereby the added inertia of larger switches may be overcome by the use of a double spring toggle to insure a quick make and break of the switch when actuated.

In order to apprise those skilled in the art how to construct and practice my invention, I shall now describe a preferred embodiment thereof in connection with the accompanying drawings which form a part hereof:

In the drawings:

Figure 1 is a front elevational view of an enclosed switch embodying my invention, the cover of the switch being broken away to show the relation of the interlocking mechanism to the main structure of the switch;

Fig. 2 is a side elevation of the switch;

Fig. 3 is a side elevational view of the interlocking mechanism and relay connection, the side wall of the switch box being omitted, and moreover, the near side wall of the interlocking mechanism housing being broken away to disclose clearly the interlocking elements—only that portion of the switch operating mechanism which cooperates directly with the interlocking mechanism being shown. In this figure the interlocking elements are positioned as they are when the cover is closed and the switch is open;

Fig. 4 shows the interlocking elements as they appear when the cover is closed and the switch is closed;

Fig. 5 illustrates the position of the interlocking elements and relay connection when both the cover and the switch are open;

Fig. 6 illustrates the interlocking elements and relay connection as rendered inoperative by a key, the switch having been closed while the cover remained open;

Fig. 7 is a top plan view of the relay connection;

Fig. 8 is a detail view of the inner side of the lost motion connection between the switch and switch handle;

Fig. 9 illustrates the key employed to disable the interlocking mechanism;

Fig. 10 is a plan sectional view of the unitary casing containing the interlocking mechanism showing the manner in which the key engages the various controlling elements;

Fig. 11 is a side elevational view showing a cover latch associated with the interlocking

elements of the switch, the latch in this figure being locked permanently in cover securing position;

Fig. 12 is another view similar to Fig. 11 and showing the same elements as formerly shown except that the cover latch in the last figure is in unlocked condition;

Fig. 13 is a fragmentary end elevational sectional view of some of the elements shown in Fig. 12 and illustrates the elements whereby an accidental locking of the cover latch is prevented; and

Fig. 14 is a side elevational view of another form of switch box wherein my improved unitary locking and interlocking cover control means may be positioned.

The switch which I have shown as embodying my invention is preferably of a larger capacity type than the one shown in said copending application, the operating elements of the present switch being of heavier construction and consequently having greater inertia. However, there is no particular capacity of switch to which my invention may be especially adapted, being on the contrary capable of embodiment in a switch of any capacity. I desire to state, however, that in practice I contemplate embodying the relay connections, constituting the essence of the present invention, more particularly in switches of capacities of 200 amperes or over. This is due to the fact that in switches of such capacities it is necessary to make the moving parts of greater weight and larger size in order to properly carry the current. This increase in weight and size permits sufficient force to be placed in back of the effort to close the switch while locked in open position, so that permanent disablement or jamming of the interlocking mechanism is possible if employed alone. The relay connections are, therefore, provided to carry the excessive load resulting from this attempt to force the switch closed while the cover is open. I wish it to be understood that the relay connections may be embodied in switches of any capacity, and therefore, do not limit myself to any size or capacity of switches.

Referring more particularly to the drawings, a switch box 5 is provided with a hinged cover 6. Disposed in the interior of the box 5, and upon the back walls thereof, are a plurality of base units 7 for properly carrying the switch contacts. The base units 7 are individually secured to the back wall of the switch box 5 by means of screws 8 which pass through opposite flanges 9 on these base units and enter the back wall of the switch box. The base units 7 are preferably of insulation material.

The advantages of this unit base construction are more fully described and specifically claimed in the copending application of Albert P. Ball, Serial No. 623,356, filed March

7, 1923, for Unit base construction, the same being assigned to the Square D Company.

On these base units 7 are mounted switch contact clips 10, which are bridged by a movable contact 11, the latter being actuated by a switch operating handle 17, which lies on the exterior of the switch box and connects to said movable contact 11 through a lost motion connection which will be presently described.

Referring more particularly to Fig. 8, a rigid base 15 carries a vertical plate 16, rigidly secured thereto, which plate 16 serves as a journal for the inner end of switch handle 17, the side wall of the switch box serving as a second point of support for this handle. Loosely mounted on the handle 17 is a member 18, preferably disposed between the side wall of the cabinet and the short end of the bail member to which the movable contact 11 is connected. Right angular lugs 19 and 20 are provided on the member 18 and are of such length as to lie in the path of movement of the bail member and a finger 21 fixed to the handle 17. As shown in Fig. 8, a pair of toggle rods is arranged, preferably one on each side of the member 18, to provide a quick make and break action to the opening and closing of the switch. On the right of member 18, a rod 24 is loosely pinned thereto, with the opposite end projecting through and being confined in the opening in the rigidly secured plate 26. A coil spring 25 encircles rod 24, being confined between the lost motion plate 18 and the rigid plate 26. On the opposite side of this plate 18 a similar rod 27 is disposed, being also loosely pinned to plate 18, but, in this instance, serving as a connection between switch operating mechanism and the interlocking mechanism 30, which will hereinafter be described. A coil spring 28 surrounds the rod 27 having one end confined at the point where the rod is loosely pinned to the member 18, and the other end confined against one side of the housing in which the parts of the interlocking mechanism 30 is disposed. The springs 25 and 28 are adapted for compression and expansion at various predetermined times during the opening and closing movement of the switch operating mechanism, whereby a quick make and break is provided between the movable blade 11 and the switch contacts 10. By providing these springs 25 and 28, a double spring toggle is obtained. During the initial movement of the switch handle 17, the springs are compressed. As soon as moved past their dead center position, the energy stored up in the springs will cause an accelerating movement of the switch, either to open or closed position. The added energy of the second spring functions to increase the effort in back of the accelerating movement, and insures a quick and positive action of the switch. We shall now describe

115
120
125
130
135

the lost motion connection between the switch handle 17 and the switch.

The inner end of the handle 17 is preferably cut rectangular, and upon this rectangular end the finger 21 is fixed. Finger 21 is adapted to move between the projecting lugs 19 and 20 on the lost motion plate 18. It is to be noted that the side arm of the bail member 31 is confined between finger 21 and lost motion plate 18. This end of the bail member 31 is loosely journaled around the inner end of the switch handle 17. In the operation of the switch, this end of the switch handle 17 will bring the finger 21 into engagement either with the lug 19 or with the lug 20, as the case may be, and move the lost motion plate 18 against the tension of the springs 25 and 28 until these springs have moved past their dead center position whereupon the accelerating movement caused by the springs will quickly bring the opposite lug 19 or 20 into engagement with the bail member 31. Thus the switch is forced quickly to make or break contact.

A finger hold 35 is mounted on the top of the hinged cover 6, whereby said cover may be readily opened with one finger of the hand while another finger thereof presses back a spring latch 36. We find that this close relation of the two elements just mentioned is very convenient. A member 37 is fastened to the inner side of the cover and is apertured to constitute a cover hasp.

As clearly shown in Figs. 1 and 2, a housing 38, which contains the interlocking elements, and if desired, the cover latch 36, is of such a shape that it may be positioned anywhere in the switch box and occupy a negligible amount of space within the box. This housing is provided with a plurality of perforations: one designated 40 through which the cover latch 36 extends, another designated 41 through which the hasp 37 extends into operative relation with the elements 45 within the housing when the cover is closed, still another designated 42 in the end of the housing through which is adapted to pass that portion of the switch operating mechanism which is operatively associated with the interlocking element within the housing—in this case being the toggle rod 27—and one designated 43 which is a key hole through which a proper key may be inserted for the purpose of disabling the interlocking mechanism 30, as will be later described. It should be noted that the side of the switch box is apertured at 44 whereby, when the housing is properly positioned, said aperture 44 registers with the key aperture 43 in the housing. Bolts 45 pass through the wall of the switch box and the housing and serve to hold, in detachable relation, the housing in correct position with respect to the elements which are to be interlocked.

A cover lock member 46 is pivotally mount-

ed upon a pin 47, which extends transversely between the side walls of the housing 38. This member 46 is provided with an upper hook portion 48, and on the other side of its pivotal point with an abutment portion 49. It is urged to the right, or into locking position, by one arm 50 of the coil spring 52, the latter being wound around the pivoted pin 47.

A cam member 53, also pivotally mounted on the pin 47, is urged upwardly by another arm 54 of the spring 52. In its locking position, that is, when urged upwardly to the limit of its movement in that direction, a re-entrant portion 55 thereof engages the hook end 56 of the toggle rod 27 and prevents its movement. Figs. 4 and 5 best illustrate the manner in which the toggle rod of the switch operating member is locked. Member 53 is also provided, on the other side of its pivotal point from the reentrant portion 55, with an abutment portion 58.

A member 59 functions both as a protective cam at certain times during the operation of the switch and as a controlling member for the cam member 53. This member 59 is pivotally mounted on a pin 61, and is normally urged into the position of Fig. 6 by the action of the coil spring 62, one arm 63 of which engages around the portion 64 of the member 59. This member is also provided with a portion 65 which, it will be observed in Figs. 5 and 6, is positioned directly beneath the aperture 41 through which the hasp 37 enters the housing while the cover 6 is open. A guide member 66 is positioned as shown.

Between the bracket member 68 and the front wall of the housing 38, is supported a key cylinder 69, this cylinder being adapted to receive and turn with the key 70. This key is provided with ward portions 71 and 72, which are adapted, when said key is turned, to engage the members 46 and 53, respectively, to turn them about their pivots against the action of spring 52, and thereby render their locking function ineffective.

Before proceeding with a description of the part of my invention which relates to the relay connection, I deem it preferable to describe first the operation of the interlocking mechanism 30.

Attention is first directed to Fig. 3 where-in the position of the various elements when the cover is closed, but with the switch still open, is illustrated. This figure should be considered in connection with Fig. 5, the latter showing the elements as they appear when the cover is open and before the switch is open. It will be noted that while the switch is in its open position, the hook portion 56 of the toggle rod presses against the abutment portion 49 of the member 46 and moves the member 46 against the action of the spring 52, so that the hook 48 disengages the hasp 37. Referring to Fig. 5, it will be noted

that when the member 53 is urged upwardly by the spring arm 54, the hook end 56 of the toggle rod 27 is situated in the reentrant portion 55. If, therefore, while the cover is open, an effort be made to close the switch, the end 56 of the rod 27 will be first moved to the right in the position shown in Fig. 5 and will thus strike the shoulder 55' on the right hand side of the reentrant portion 55, whereby the closing movement of the switch will be prevented. This action is clearly shown by the dotted lines illustrating the locus of movement of the end 56 on the toggle rod 27.

Considering now in Fig. 3 the situation as existing after the cover has been closed, it should be first understood that as the cover closes, the hasp 37 passes through the aperture 41 and the lower edge thereof presses against the upper edge of portion 64 of the member 59, pushing the latter downwardly to the left around pivot 61 against the action of the spring 62. As the member 59 turns and the portion 65 moves downwardly, the portion 64 swings to the left and enters the aperture 75 in the hasp 37. It should be noted that the free end of the portion 64 is turned at right angles to the plane of the member 59, whereby a transverse obstruction extends across the housing and under the aperture 41 when the member 59 is swung downwardly to the left. This provision is most advantageous since it prevents the insertion of a nail, wire, or other instrument to push the member 59 downwardly to effect a release of the interlock, this latter feature not yet having been described. That is, although an instrument may be introduced as far as the portion 65 to move the same slightly downwardly, it is obvious that as soon as the portion 64 comes beneath the aperture 41, it will at once block any further movement of said instrument thus introduced.

Considering further the action of the portion 65 as it moves downwardly, I find that it comes in contact with the abutment portion 58 of the cam member 53, and since they are coplanar, the edge to edge engagement of said members 59 and 53 serves to move the member 53 downwardly against the action of the spring 52. When the downward movement of the member has been accomplished, it will be observed, as clearly shown in Fig. 3, that the reentrant portion 55 no longer engages the end 56 of the toggle rod, and the latter is, therefore, free to move along its locus, shown in Fig. 4, and not be obstructed in such movement by the member 53.

The elements in Fig. 3 are positioned as they appear after the cover of the box has been closed. The exterior operating handle may now be moved to switch closing position. During this movement the end of the toggle rod 27 will move from the position shown in Fig. 3 to the full line position shown in Fig. 4. It should be observed first, how-

ever, that in Fig. 3 the hook 48 has not entered the aperture 75 of the hasp 37, the normal action of the spring being opposed by the positive engagement of the toggle end 56 with the abutment portion 49 of the member 46. However, as the toggle rod moves away from the abutment portion 49, that is, as soon as the switch is moved to its closed position, the spring arm 50 urges the hook 48 into engagement with the hasp 37. This position is shown in Fig. 4, wherein it may be noted that the cover cannot be opened while the hook 48 extends fully into the aperture 75 of the hasp 37, and prevents the withdrawal of the latter from the exterior of the housing. At the same time, as hereinbefore indicated, the member 59 maintains member 53 in its lower position, whereby the end of toggle rod 56 may freely travel through its locus as indicated in Fig. 4.

Assuming now, that with the cover closed and the switch closed, it is desired to open the cover without affecting the position of the switch contacts. The manner in which this may be accomplished is illustrated in Fig. 6. The key 70 is inserted through the key hole and it is, of course, understood that I contemplate providing a key of particular formation having wards thereon, so shaped and positioned that only a key which conforms to all of the required settings may be used. After inserting the key, the same is turned to the left, whereupon the ward portion 71 engages the edge of the member 46 and presses it to the left. The hasp 37 may then be withdrawn from the interior of the housing and the cover opened. If, on the other hand, the cover is open and the switch is likewise open, the key may be utilized to disable the interlock and permit the closing of the switch while the cover is open. With the switch as shown in Fig. 5, the key is inserted and upon being turned to the left, ward 72 thereof presses against a portion 72a of the member 53 and turns the latter downwardly to the right whereby the toggle end 56 is released from the reentrant portion 55. The switch operating mechanism may then be moved to switch closing position since there is no longer any obstruction in the path of movement of the toggle rod 27.

From the foregoing it will be observed that access to the interior of the switch box 5 while the switch is closed may be had only when the attendant has been provided with key 70 to disable the interlocking mechanism 30. If he has no key, then access to the interior of the switch box is possible only when the switch has been opened to release the cover. It is when the switch is open and the cover is open that the interlocking mechanism is apt to be permanently disabled or mutilated in an attempt to then close the switch, these attempts usually being made, of course, by unauthorized persons. We have found from

experience that unauthorized persons in some cases, may be able to apply such force to the handle as will cause the toggle rod to bend, or the interlocking mechanism to jam by the 5 end 56 of the toggle pressing against the shoulder 55' with such force as to overcome the action of spring 52. However, this is true only in those switches where the operating parts are of sufficient size to permit the 10 application of such a force. It is apparent that in smaller capacity switches, it is not possible to apply this force, and therefore, the interlocking mechanism 30 and toggle rod 27 thereof are sufficient to protect the locking 15 of the switch in open position while the cover is open. But, as hereinbefore stated, the moving parts of switches of 200 amperage capacity, and over, are large enough to transmit the aforesaid force and cause destruction to 20 the interlocking mechanism in an effort to close the switch while the cover is open.

As before pointed out, my invention contemplates the use of a relay connection 80 with the standard interlocking mechanism 30 in switches where the latter is apt to be jammed or mutilated while the cover is open. This relay connection may be applied to the 25 larger capacity switches without requiring a revision of the standard interlocking mechanism.

As shown in the drawings, the relay connection 80 comprises a rod 81 having a pair of bell crank levers 82 and 83 at the ends thereof. Bell crank lever 82 is pivotally mounted 30 on the horizontal portion 84 of the vertical plate 16, as clearly shown in Fig. 7. According to the drawings, this bell crank lever is disposed in a horizontal plane, and is adapted 35 to swing in the path of the lost motion plate 18 by engaging in the notch 85 cut in the lower edge of said lost motion plate. Bell crank lever 82 serves more particularly as a finger wedge and allows the plate 18 to be pressed thereagainst with as much force as 40 can be applied through the switch handle in an attempt to close the switch while the cover is open. From Fig. 5 it will be seen that the upper edge of the groove 85 engages 45 the top face of the bell crank lever 82. Thus a surface engagement between these members is obtained, and consequently, it is practically impossible to destroy the finger wedge 82, much less is it impossible to cause it to swing 50 out of the path of the plate 18, as its movement is in a plane at right angles to that of the plate 18. This is clearly shown in Fig. 7.

Bell crank lever 82 may be attached to the 55 horizontal portion of the vertical plate 16 in any suitable manner, and the rod 81 may connect with the bell crank lever 82 in any preferable way. It is not essential that these attachments be such that disconnection of these members is impossible, for if the relay connection is disabled, the interlocking mechanism, as will be later seen, is still effective to

prevent the closing of the switch. I have found that the circumstances under which these switches are mutilated by jamming the interlocking mechanism are such that it does not warrant making the relay connection absolutely tamper-proof, because the workmen usually do not care to jeopardize their relation with their employer by such acts.

The opposite end of the rod 81 is connected to the bell crank lever 83. Bell crank lever 75 83 is pivotally mounted at the side of the switch box by means of a pin 87, riveted at one end in the side of the switch box. The horizontal arm 88 of the bell crank lever 83 engages the lower edge of the switch lock 80 member 53, being held thereagainst by means of a spring 89. One end of spring 89 connects to the lower arm of the bell crank lever 83, while the other end connects to a screw 91 projecting inwardly from the side of the 85 switch box. Inasmuch as the bell crank lever 83 is at all times urged into engagement with the lower edge of the member 53, it will tend to follow said member in its movement. Referring now to the operation of the relay connection 80, it will be seen from Figs. 3 and 7 that with the switch lock member 53 in its normal or upper position the bell crank lever 83 will also be in its upper position, causing the rod 81 to swing the finger wedge 82 in 90 the groove 85. This will prevent the switch handle from moving the lost motion plate 18 in switch closing direction. Thus it is impossible to close the switch. Two interlocks 95 are thereby provided, one by the interlocking 100 mechanism 30 and the other by this relay connection 80, which is controlled by the interlocking mechanism.

However, when the cover is closed, as 105 shown in Fig. 3, the switch interlocking member 53 is forced downwardly by means of the member 59 swinging to the left and the portion 65 thereof engaging the abutment 58 and forcing the switch lock member 110 to the right about its pivot 47. This movement of the switch lock member 53 forces the bell crank lever 83 downwardly against the tension of the spring 89, thereby causing the rod 81 pivotally to withdraw the finger wedge from without the groove 85. The 115 lost motion plate 18 is then allowed to swing about its pivot to close the switch.

A shoulder 95 has been provided on the lost motion plate 18 for the purpose of serving as a stop member for the plate in its movement to switch closing position, the switch closing, of course, with considerable force as the result of the two toggle springs 25 and 28, and therefore requiring a stop 120 to check the accelerating action imparted to it near the end of its movement. This will permit the switch blades 11 to engage the contacts 10 without placing any strain upon the same. Likewise, when the switch 125 is opened, the accelerating action of the lost 130

motion plate 18 in its movement in this direction is checked by a shoulder 96 on the plate which also serves as a stop member. In either case, therefore, the added force, resulting from the double toggle mechanism and provided for the purpose of overcoming the increased inertia of the moving parts of the larger switches, does not tend to strain the switch structure, these stop shoulders serving to check the lost motion plate by engaging the horizontal portion 84 of the vertical plate 16.

When the key 70 is employed to disable the interlocking mechanism 30, in order to close the switch while the cover is open, the action of the relay connection is substantially the same as hereinbefore described. Moving the key to the left, as shown in Fig. 6, causes the ward 72 to engage the switch lock member 53 and move it downwardly. The downward movement of the switch lock member 53 causes the bell crank lever 83 also to move downwardly, with the result that the finger wedge 82 is withdrawn from the path of movement of the lost motion plate 18. The switch may now be closed by movement of the switch handle 17, the lost motion plate 18 which is mounted on the switch handle being allowed to turn without obstruction by the finger wedge or barrier lever 82.

While I have not elaborated on the action of the relay connection 80 when the cover 6 is closed and the interlocking mechanism moved to permit the closing of the switch, it may be noted, however, that the relay connection will be actuated by the closing of the cover, to withdraw the barrier lever 82 from the groove 85 in the lost motion plate 18. Thus both of the switch interlocks are simultaneously disabled by the closing of the cover.

The switch interlocks are, moreover, also disabled simultaneously by the disabling key 70 which preferably operates to disable the relay connection 80 through the interlocking mechanism 30. I, however, do not intend to limit myself to such a relation between the interlocking mechanism, relay connection and disabling device, as it is apparent that slight modifications, within the scope of my invention, might be made whereby independent action of the interlocking mechanism and relay connection might be had.

I wish to point out the manner in which the entire strain or load is placed upon the relay connection instead of the interlocking mechanism, when any attempt is made to force the switch closed while locked in open position, but here again I do not intend to limit myself to the specific structure shown. The groove or recess 85 cut in the lost motion plate 18 is slightly larger in a vertical direction than the thickness of the barrier lever 82, so that the latter when actuated may easily slide within the former. Consequently

a small space, being negligible however, is left between the top face of the barrier lever 82 and the lower edge of the plate 18. If so desired, this space may be omitted, but for mechanical reasons it is preferable. If an attempt is now made to force the switch closed while the cover is open, the switch handle may be moved slightly until the lower edge of plate 18 strikes the top face of barrier lever 82. As shown in Fig. 6, the lever 82 is flatly supported upon the horizontal portion 84 of plate 16 carried upon the rigid post 15, and therefore, can not be displaced. Hence the switch handle can not be moved any farther and attempts to jam the switch interlock are frustrated.

The interlocking function of the relay connection 80 acts in advance of that of the interlocking mechanism 30. This prevents any strain, resulting from attempts to force the switch closed, upon the interlocking mechanism. By referring to Fig. 5 it will be seen that the end 56 of the toggle rod 27 is required to move a certain distance, in the re-entrant portion 55, before it engages shoulder 55' on the switch lock member 53. This distance is slightly greater than the aforesaid space between the top face of barrier lever 82 and the lower edge of plate 18. Hence, the end 56 of toggle rod 27 will not engage shoulder 55' before the plate 18 engages barrier lever 82, and the interlocking mechanism 30 will not be required, therefore, to carry said strain. This strain is placed upon the barrier lever 82 and the vertical post 15, and is not transmitted by the rod 81 to the interlocking mechanism.

In my aforesaid copending application, I have disclosed a spring cover latch which may be used to lock the switch box cover 6 permanently closed. This cover latch is mounted on pin 61 of the disabling device and is operated by the key 70 by turning it in a direction reversed to that required to disable the cover lock member 46 and the switch lock member 53. Although it has not been illustrated in the present instance, I wish it to be understood that this permanent spring cover latch may be embodied in the present device and obtain all the advantages accruing from its use.

The aforesaid spring cover latch is an additional feature which has been demanded by the switch using public. I have found that there is an insistent demand for a positively latched cover in an enclosed switch. Furthermore, such demand is present even though the switch in question may be provided with an interlocking mechanism. There are numerous reasons for this demand on the part of switch users—not the least of which is the wish to have permanently associated with the enclosed switch some device whereby the cover may be locked closed even though the switch is open. It will be remem-

bered, of course, that, in an interlocked switch of the character heretofore discussed, as soon as the switch is thrown to open position, the cover may be opened.

5 It appears preferable therefore to incorporate at some point on the body of the switch box, a latch (hereinafter illustrated as one of spring type) which would engage the cover when the same is closed and which can be 10 utilized to permanently lock the cover closed by a padlock. This simple expedient, however, is apparently not open to the manufacturer of switches, which are to embody both the interlocking and cover latching features.

15 In order that the interlocking mechanism may function properly it is quite essential that the cover of the box close snugly thereupon, and I have found that a cover latch quite often interferes with the normal operation 20 of the interlock. This last occurs because of the natural lightness, and consequent tendency to spring, of the material of which the cover is made. Then again it is my desire, if the customer wishes a switch 25 box having both the interlocking means and the cover latch, to simplify the structure by associating these two features in such manner that an extremely simple cover control will be eventuated.

30 In pursuance of this object I associate a cover latch with the interlocking mechanism in such manner that said latch may be positively locked, when desired, by the same key which I have heretofore mentioned as controlling 35 the disablement or release of the interlock mechanism. By so positioning the latch and by utilizing a key to effectuate the locking thereof, I eliminate altogether the bothersome padlocks which have been 40 almost universally employed in permanently locking the covers of enclosed switches.

Having provided a structure wherein the same key may either disable the locking mechanism or serve to lock the cover latch, I find 45 that an additional feature is quite desirable. While the reason for this additional feature will be better understood after a reading of the description of the switch itself, I may here state that some means must be provided 50 which will prevent the inadvertent locking of the cover latch. I find, for instance, that when the switch box cover is open and an inspector has inserted the key for the purpose of releasing the switch operating mechanism, he may inadvertently so turn the key 55 that the cover latch is locked. If now the cover switch be slammed closed a destruction of the entire interlocking mechanism may occur. Then, too, if the locking latch is not utilized, or its use is not understood by the inspector he may inadvertently lock the same and thereafter be unable to understand why he cannot close the cover.

60 A further object of my invention, therefore, is to provide means which will posi-

tively prevent the inadvertent locking of the cover latch when it is only desired to disable the interlock. Such means may be pertinently defined as "selective" means since their embodiment in the switch necessitates 70 a definite selection between the two sets of locking or cover controlling elements—that is, the operator must definitely select either the permanent latch feature as controlling the cover movement, or he may desire to depend on the interlocking mechanism for the control of the movement of the cover. Therefore, I hereafter refer to the key and its associated mechanism as the means whereby the 75 particular type of cover control which the operator desires is selected.

It is my further desire to provide an interlocking mechanism which will be available to all users of switches, whether they were initially intended to embody such features 80 or not. That is, I propose to embody my invention in a device of such character that it can be applied to switches which are already installed if the user of the latter desires to avail himself of the advantages which are 85 incident to the embodiment of my interlock in an enclosed switch. I, therefore, embody my interlock and, if desired, my cover locking latch, in a unitary structure which may be readily applied to most enclosed switches 90 without altering in any manner the essential and fundamental elements of the switch operating mechanism. With this object in view I dispose my interlocking mechanism, as well as the cover latch if desired, in a housing 95 which may be applied to substantially all enclosed switches. Of course, it should be understood that, conversely, if for any reason it is desired to remove the interlocking feature entirely from those switches in which 100 it is initially furnished this can be done quite simply and expeditiously since the unitary construction of my mechanism enables it to be either applied to, or removed from, a switch box with a minimum effort and alteration 105 of the switch.

In conformity with the above desire to provide a selective cover controlling system, I provide the structure shown in Figs. 11, 12, 110 13 and 14 which latter embody, together with all the other desirable interlocking features heretofore discussed, a cover latch which is normally spring operated and by means of which the cover may be permanently locked 115 shut, irrespective of the position of the switch operating elements. It will be understood, of course, that this latch may be included when the customer so desires, or it may be omitted. In case it is desired, I wish to direct attention to the extremely expeditious 120 manner in which it is utilized, and I further wish to emphasize the ease with which the user of a switch of this character may select which of the two types of cover control he 125 desires to employ.

In Fig. 11 the cover latch 36 is pivotally mounted on the pin 61, and after passing through an aperture 6a on the cover is urged into locking position by the arm 63a of the spring passing around the pin 61. This latch 36 is faced as shown in order that if the cover is closed, the latch may be pushed to the left, the reentrant portion 36b of the latch engaging the cover after the latter has been completely closed, this by reason of the fact that said latch is constantly urged to the right. The latch 36 is provided with a downwardly extending portion 36a, which portion moves to the right as the upper end of the latch is pressed to the left.

Rotatably mounted on the key cylinder 69 is a locking member or disc 69a which is provided with a hooked locking portion 69b, it being understood that the latch 36 and the disc 69a lie in the same plane wherefrom the hook 69b engages the extreme lower end of the portion 36a and holds the latch in locked relation with the cover when said elements are engaged as shown in Fig. 11.

It will be observed that this locking disc 69a may be turned into locking position (as shown in Fig. 11) by turning the key 70 approximately 30° to the right. The said disc 69a is provided with pits or openings 69c which receive a ratchet point 69d mounted on a spring member 69e. The latter member 69e is secured to the wall of the housing and is so tensioned that the point 69d is constantly urged toward and into the openings 69c in the member 69a. Because of this latter construction, an appreciable twist is required to move the locking disc 69a to the right to lock the cover latch. However, when the latch has been locked the cooperating pawl and latching device insure its permanency in the locked position against jarring or other inadvertent movement.

As we have before intimated, there is a chance that someone may insert the key for the purpose of disabling the interlocking mechanism and inadvertently move said key slightly to the right whereupon the cover latch may be locked and undesirable consequences result because of such inadvertent locking of the latch in its extreme right-hand position. I have, therefore, provided means which insure against such inadvertent locking.

A spring member 69f is mounted on the wall of the housing (see Figs. 12 and 13) and has its lower end 69g normally positioned to engage the hook portion 69b and prevent the movement of the locking disc 69a to the right. A push button 69h extends through the wall of the switch box and provides means whereby the spring 69f can be moved inwardly (to the left in Fig. 13) to disengage the lower end 69g and the hook 69b.

When the operator has deliberately and positively pushed button 69h and effected the

disengagement of the hook 69b from the lower end 69g of the spring member 69f, such operator may then turn the key to the right whereupon the hook 69b will travel upwardly and engage the lower end 36a of the latch 36, as shown in Fig. 11, whereby said latch 36 is locked in its cover latching position. To obtain access to the switch enclosure, it will now be necessary to insert the key in the keyhole 40 and turn said key 30° to the left whereupon the cover latch 36 will be released and the cover control mechanism of the interlock will be restored to its normal position.

It will be understood, therefore, that I have provided means which require that the operator of the switch knowingly select the particular type of cover control which he desires. This selection is made easy since the same key is utilized for both kinds of cover control; merely the reversal of direction in the twist being necessary to change the enclosed switch from one in which the cover is controlled only by a latch to one wherein the interlocking feature predominates. Even though I have associated this last described latching feature with my device, I have rendered it no less unitary and capable of application to both old and new enclosed switches. I believe I am the first to appreciate the necessity for supplying the increasing demand for safety switches and at the same time reconciling the various apparent diverse requirements of the users of this switch.

As pointed out in the foregoing description, I have provided an enclosed switch locking aggregate which makes available to the user any of a number of methods of cover control. Moreover, I have made the selection of the desired type of control quite easy whereby the user is enabled to select the desired control by merely turning a key. And finally I feel that the provision of means whereby the selection must be made, positively removes the only chance which there might be of inexperienced operators inadvertently causing an undesirable type of cover control to function. As above indicated, the advantages incident to the varied cover control system are made available to users of old style switches as well as to those who initially adopt my switch. This change is made easy because of my unitary detachable construction.

In Fig. 2, an apertured member 90 having an aperture therein projects through an opening in the cover 6 from the interior of the switch box 5. If so desired, a padlock (not shown) may be used to lock the cover permanently closed.

As I have hereinbefore pointed out, the interlocking mechanism 30 and relay connection 80 constitute two separate and distinct interlocks. It is, therefore, apparent that fundamentally my invention extends to such variations in the construction of switches of

the type shown herein as would separate these interlocks and have them operate independently, inasmuch as I intend primarily to provide a device for preventing the jamming or rupturing of the standard interlocking mechanism on switches of larger capacity. Likewise it would extend to a structure wherein these interlocks might be operated individually by cover hasps similar to hasp 37 on cover 6, and also be disabled by individual disabling devices.

Though I have described with great particularity of detail a preferred embodiment of my invention, yet it is not to be understood therefrom that the invention is restricted to the specific embodiment described. Various modifications thereof, in detail and in the arrangements of the parts may be made by those skilled in the art, without departing 20 from the spirit and scope of the invention.

I claim:

1. In combination with a switch box having a cover thereon and switch operating mechanism therein, an interlocking mechanism whereby the cover can not be opened while the switch is closed nor the switch closed while the cover is open, a housing in which said mechanism is disposed, and a relay connection exterior of said housing but cooperating with said interlocking mechanism and said switch operating mechanism for also preventing the closing of the switch while the cover is open.

2. In combination with a switch box having a cover thereon and switch operating mechanism therein, an interlocking mechanism, a connection between said interlocking mechanism and said switch operating mechanism, and a second connection controlled by said interlocking mechanism for interposing a barrier in the path of said switch operating mechanism while said cover is open.

3. In combination with a switch box having a cover thereon and switch operating mechanism therein, an interlocking mechanism whereby the cover can not be opened while the switch is closed nor the switch closed while the cover is open, a housing in which said mechanism is disposed, a relay connection between said switch operating mechanism and said interlocking mechanism for relieving the latter of any strain as the result of an attempt to force said switch closed while the cover is open, said connection cooperating with said interlocking mechanism at one side of said housing.

4. In combination with a switch box having a cover thereon and switch operating mechanism therein, a pair of interlocks for said switch operating mechanism whereby the switch can not be closed while the cover is open, one of said interlocks controlled by the other interlock and receiving the strain resulting from an attempt to force said switch closed while the cover is open.

5. In combination with a switch box having a cover thereon and switch operating mechanism therein, a pair of interlocks for said switch operating mechanism whereby the switch can not be closed while the cover is open, one of said interlocks controlled by but preventing the permanent disablement of the other.

6. In combination with a switch box having a cover thereon and switch operating mechanism therein, an interlocking mechanism whereby the cover can not be opened while the switch is closed nor the switch closed while the cover is open, and means controlled by said interlocking mechanism and constituting a reinforcement for the interlock when holding the switch open while the cover is open.

7. In combination with a switch box having a cover thereon and switch operating mechanism therein, an interlocking mechanism for preventing the closing of the switch while the cover is open, and means controlled by said interlocking mechanism for also locking the switch open while the cover is open, said means acting in advance of said interlocking mechanism in order to prevent permanent disablement of the latter by an attempt to force the switch closed.

8. In combination with a switch box having a cover thereon and switch operating mechanism therein, an interlocking mechanism for preventing the closing of the switch while the cover is open, means for also locking the switch open while the cover is open and functioning in advance of the locking action of said interlocking mechanism in order to prevent the permanent disablement of the same by an attempt to force the switch closed, said means including a pivotally mounted member, said member being urged into engagement with said interlocking mechanism whereby said means may be controlled thereby.

9. In combination with a switch box having a cover thereon and switch operating mechanism therein, an interlocking mechanism for preventing the closing of the switch while the cover is open, and additional means for also preventing the closing of the switch while the cover is open, said means including a spring urged member engaging a portion of said interlocking mechanism.

10. In combination with a switch box having a cover thereon and switch operating mechanism therein, an interlocking mechanism for preventing the closing of the switch while the cover is open and including a switch locking member, additional means for also preventing the closing of the switch while the cover is open, said means including a spring urged member adapted to engage said switch locking member and be controlled thereby.

11. In combination with a switch box hav-

- ing a cover thereon and switch operating mechanism therein, an interlocking mechanism for preventing the closing of the switch while the cover is open, additional means for preventing the closing of the switch while the cover is open, said switch operating mechanism being provided with a notch therein, said means including a movable member adapted to lie in said notch while the cover is open to prevent the closing movement of said switch operating mechanism. 5 70
12. In combination with a switch box having a cover thereon and switch operating mechanism therein, an interlocking mechanism for preventing the closing of the switch while the cover is open, a rod between said switch operating mechanism and interlocking mechanism, a barrier at one end of said rod, said rod being actuated by said interlocking mechanism to project said barrier in the path of said switch operating mechanism when said cover is open whereby a double interlock prevents the closing of the switch. 15 75
13. In combination with a switch box having a cover thereon and switch operating mechanism therein, an interlocking mechanism for preventing the closing of the switch while the cover is open, said mechanism embodying pivoted switch locking means for locking the switch closed through the medium of an element projecting from said operating mechanism, said switch locking means having an engageable surface and adapted when in normal position to lock said element whereby the switch is held in open position, a second element projecting from said switch operating mechanism and contacting with said engageable surface, said second element also functioning to interlock the switch in open position when said pivoted switch locking means moves to normal position. 20 80
14. In combination with a switch box having a cover thereon and switch operating mechanism therein, an interlocking mechanism for preventing the closing of the switch while the cover is open, an element connected to said switch operating mechanism and adapted to be engaged by a switch locking member normally urged into locking relation therewith and comprising part of said interlocking mechanism, a second element having one end adapted to lie in the path of said switch operating member, the other end of said second element being urged into engagement with said switch locking member, said switch locking member controlling the movement of said second element. 25 85
15. In combination with a switch box having a cover thereon and switch operating mechanism therein, an interlocking mechanism whereby the switch can not be closed while the cover is open, a toggle rod serving as a connection between said switch operating mechanism and said interlocking mecha- 30 90
- nism, and means for removing the strain from said toggle rod when an attempt is made to force said switch closed comprising a second connection between said interlocking mechanism and said switch operating mechanism. 95
16. In combination with a switch box having a cover thereon and switch operating mechanism therein, an interlocking mechanism whereby the switch can not be closed while the cover is open, a rod serving as a connection between said switch operating mechanism and interlocking mechanism, a second rod between said mechanisms, and a pivotally mounted arm at each end of said second rod. 100
17. In combination with a switch box having a cover thereon and switch operating mechanism therein, an interlocking mechanism whereby the switch can not be closed while the cover is open, a rod serving as a connection between said switch operating mechanism and said interlocking mechanism, a second rod between said mechanisms, and pivotally mounted bell crank arms connected at each end of said second rod for cooperation with said switch operating mechanism and said interlocking mechanism. 105
18. In combination with a switch box having a cover thereon and switch operating mechanism therein, an interlocking mechanism between said cover and said switch operating mechanism whereby the switch can not be closed while the cover is open, means for providing a second lock for said switch operating mechanism in order to prevent disablement of said interlocking mechanism upon an attempt to force said switch closed, said means comprising a connecting member having a pivotally mounted member at each end, one of said members adapted to serve as a barrier to prevent the movement of said switch operating member, the other member controlling the position of the first member and cooperating with said interlocking member. 110
19. In combination with a switch box having a cover thereon and switch operating mechanism therein, an interlocking mechanism between said cover and said switch operating mechanism whereby the switch can not be closed while the cover is open, means for providing a second lock for said switch operating mechanism in order to prevent the disablement of said interlocking mechanism, said means being controlled by said interlocking mechanism and being simultaneously effective therewith, said means including pivotally mounted members, one serving as a barrier member and the other as a controlling member. 115
20. In combination with a switch box having a cover thereon and switch operating mechanism therein, an interlocking mechanism between said cover and said switch operating mechanism whereby the switch can 120
- 125
- 130

- not be closed while the cover is open, means for providing a second lock for said switch operating mechanism in order to prevent the disablement of said interlocking mechanism, said means being controlled by said interlocking mechanism and being effective when the latter is effective, said means comprising a connecting member having pivotally mounted members at the ends thereof, 5 one serving as a barrier member adapted for projection in the path of said switch operating mechanism by the actuation of the other member which is arranged to cooperate with said interlocking mechanism.
- 15 21. In combination with a switch box having a cover thereon and switch operating mechanism therein, an interlocking mechanism between said cover and said switch operating mechanism whereby the switch can 20 not be closed while the cover is open, means controlled by said interlocking mechanism for strengthening the locking action of the latter and thereby preventing a forced closure of the switch while the cover is open, said 25 means comprising a connection between said switch operating mechanism and said interlocking mechanism, said connection having a spring urged member adapted to engage a portion of said interlocking mechanism and 30 be operated thereby in order to actuate said means according to the condition of the interlocking mechanism.
22. In combination with a switch box having a cover thereon and switch operating 35 mechanism therein, an interlocking mechanism between said cover and said switch operating mechanism whereby the switch can not be closed while the cover is open, a relay connection for reinforcing the interlock by 40 engaging and preventing the movement of said switch operating mechanism while the cover is open, said relay connection including a pivotally mounted finger member disposed substantially at right angles to said 45 switch operating member and adapted to lie in the path of the latter.
23. In combination with a switch box having a cover thereon and switch operating 50 mechanism therein, an interlocking mechanism between said cover and said switch operating mechanism whereby the switch can not be closed while the cover is open, a relay connection for reinforcing the interlock by 55 engaging and preventing the movement of said switch operating mechanism while the cover is open, said relay connection including a rod the movement of which is controlled by said interlocking mechanism, and a finger-like member pivotally mounted adjacent to
- 60 said switch operating mechanism for actuation by said rod whereby the finger-like member may be swung in the path of said switch operating member to prevent its movement to switch closing position.
- 65 24. In combination with a switch box hav-

ing a cover thereon and switch operating mechanism therein, an interlocking mechanism for preventing the closing of the switch while the cover is open, a relay connection actuated by said interlocking mechanism whereby an attempt to force the switch closed while the cover is open is prevented, said relay connection being simultaneously effective with said interlocking mechanism to lock said switch in open position, said interlocking mechanism remaining effective although said relay connection may be disconnected.

70 25. In combination a switch box having a cover thereon and switch operating mechanism therein, an interlocking mechanism for preventing the closing of the switch while the cover is open, a relay connection actuated by said interlocking mechanism whereby an attempt to force the switch closed while the cover is open is prevented, said relay connection adapted to operate simultaneously with said interlocking mechanism, a housing for enclosing said interlocking mechanism and preventing disablement thereof, said connection cooperating with said interlocking mechanism at one side thereof whereby disabling said connection will not disable the interlocking mechanism.

75 26. In combination with a switch box having a cover thereon and switch operating mechanism therein, an interlocking mechanism for preventing the closing of the switch while the cover is open, a relay connection between the switch and interlocking mechanism also functioning to prevent the closing of the switch while the cover is open, and means for rendering said interlocking mechanism and said relay connection ineffective.

80 27. In combination with a switch box having a cover thereon and switch operating mechanism therein, an interlocking mechanism between said switch operating mechanism and said cover, a relay connection between said switch operating mechanism and said interlocking mechanism whereby the switch can not be closed while the cover is open, and means for rendering said relay connection ineffective.

85 28. In combination with a switch having a cover thereon and switch operating mechanism therein, an interlocking mechanism between said switch operating mechanism and said cover, a relay connection between said switch operating mechanism and said interlocking mechanism and controlled by the latter whereby the switch can not be closed while the cover is open, and disabling means for rendering said relay connection ineffective.

90 29. In combination with a switch box having a cover thereon and switch operating mechanism therein, an interlocking mechanism between said switch operating mechanism and said cover, a relay connection between said switch operating mechanism and

- said interlocking mechanism whereby the switch can not be closed while the cover is open, and key controlled means for rendering said relay connection ineffective.
- 5 30. In combination with a switch having a cover thereon and switch operating mechanism therein, an interlocking mechanism between said switch operating mechanism and said cover, a relay connection between said 70
10 switch operating mechanism and said interlocking mechanism and controlled by the latter whereby the switch can not be closed while the cover is open, and key controlled means for rendering said relay connection ineffective through said interlocking mechanism. 75
- 15 31. In combination with a switch having a cover thereon and switch operating mechanism therein, an interlocking mechanism whereby the cover can not be closed while the switch is open, said interlocking mechanism embodying a switch locking member for locking the switch open while the cover is open, means controlled by said interlocking mechanism for also locking the switch open while the cover is open, and key-like means for rendering said switch locking member and said means ineffective to release the switch. 80
- 20 32. In combination with a switch having a cover thereon and switch operating mechanism therein, an interlocking mechanism whereby the cover can not be closed while the switch is open, said interlocking mechanism embodying a switch locking member for locking the switch open while the cover is open, means actuated by said switch locking member for also locking the switch open while the cover is open, and key-like means 85 for rendering said switch locks ineffective. 90
- 25 33. In combination with a switch having a cover thereon and switch operating mechanism therein, an interlocking mechanism whereby the cover can not be closed while the switch is open, said interlocking mechanism embodying a switch locking member for locking the switch open while the cover is open, a connection between said switch operating mechanism and said interlocking mechanism, 95
30 said connection being operated by said switch locking member and providing an additional lock for the switch, and means for rendering said switch locking member and said connection ineffective. 100
- 35 34. In combination with a switch having a cover thereon and switch operating mechanism therein, an interlocking mechanism whereby the cover can not be closed while the switch is open, said interlocking mechanism embodying a switch locking member for locking the switch open while the cover is open, means controlled by said switch locking member for also locking the switch open while the cover is open, means operated by the closure of said cover to render 105
40 said switch locking means ineffective, means comprising a key having portions adapted to engage both said cover locking means and said switch locking means to nullify the locking functions of the latter two elements. 110
- 45 35. In combination with a switch having a cover thereon and switch operating mechanism therein, an interlocking mechanism whereby the cover can not be opened while the switch is closed nor the switch closed 115
50 while the cover is open, said mechanism embodying cover locking means to lock said cover closed while the switch is closed, switch locking means for locking the switch open while the cover is open, a second interlocking mechanism controlled by said first interlocking means, and means for rendering said cover locking means and said switch locking means ineffective to nullify their locking function and the locking function of said 120
55 second interlocking mechanism. 125
- 60 36. In combination, an enclosed switch provided with a movable cover and means affording an interlock for preventing the independent manipulation of the switch and cover, and means affording a second interlock reinforcing said first interlock and for also preventing the closing of the switch while the cover is open. 130
- 65 37. In combination, an enclosed switch provided with a movable cover and means affording an interlock for preventing the independent manipulation of the switch and cover, and means affording a second interlock reinforcing said first interlock and for also preventing the closing of the switch while the cover is open, and means for disabling both of said interlocks. 95
- 70 38. An enclosed switch having a cover thereon and switch operating mechanism therein, interlocking mechanism for preventing the opening of the cover while the switch is closed and for preventing the closing of the switch while the cover is open, and relay means associable with said interlocking mechanism for removing the strain from the latter when it is sought to force said switch closed while said cover is open. 100
- 75 39. In combination with a switch box having a cover thereon and switch operating mechanism therein, an interlocking mechanism whereby the cover cannot be opened while the switch is closed nor the switch closed while the cover is open, said mechanism embodying cover locking means to positively lock said cover closed while the switch is closed, switch locking means for locking the switch open while the cover is open, means operated by the closure of said cover to render said switch locking means ineffective, means comprising a key having portions adapted to engage both said cover locking means and said switch locking means to nullify the locking functions of the latter two elements. 110
- 80 40. In combination with a switch box hav- 130

- ing a cover thereon and switch operating mechanism therein, an interlocking mechanism whereby the cover cannot be opened while the switch is closed nor the switch closed while the cover is open, said mechanism embodying pivoted cover locking means to positively lock said cover closed while the switch is closed, pivoted switch locking means for locking the switch open while the cover is open, pivoted means operated by the closure of said cover to render said switch locking means ineffective, and means for moving, when desired, both said cover locking means and said switch locking means to nullify their locking functions comprising a key having portions adapted to move both said cover locking means and said switch locking means around their pivots to nullify the locking functions of the latter two elements.
41. In combination with a switch box having a cover thereon and switch operating mechanism therein, an interlocking mechanism whereby the cover cannot be opened while the switch is closed nor the switch closed while the cover is open, said mechanism embodying cover locking means, a hasp on said cover which is engaged by said cover locking means when the cover is closed to lock said cover in the latter position, said cover locking means being moved to unlocking position by the opening of said switch, switch locking means which prevents the switch closing movement of said switch operating mechanism when the cover is open, both of said locking means having a common pivotal mounting and a common spring so engaging said locking means that they are both normally urged into locking position.
42. In combination with a switch box having a cover thereon and switch operating mechanism therein, an interlocking mechanism whereby the cover cannot be opened while the switch is closed nor the switch closed while the cover is open, said mechanism embodying cover locking means, a hasp on said cover which is engaged by said cover locking means, when the cover is closed, to lock said cover in the latter position, said cover locking means being moved to unlocking position by the opening of said switch, switch locking means which prevents the switch closing movement of said switch operating mechanism when the cover is open, both of said locking means having a common pivotal mounting, a common spring so engaging said locking means that they are both normally urged into locking position, and a key adapted to engage both of said locking means to move them against said spring whereby their normal locking function is nullified.
43. In combination with a switch box having a cover thereon and switch operating mechanism therein, an interlocking mechanism whereby the cover cannot be opened while the switch is closed nor the switch closed while the cover is open, a cover latch,

while the switch is closed nor the switch closed while the cover is open, a cover latch, and means coacting with both the interlock and the latch for permitting the use of either the interlock or the latch.

44. In combination with a switch box having a cover thereon and switch operating mechanism therein, an interlocking mechanism whereby the cover cannot be opened while the switch is closed nor the switch closed while the cover is open, a cover latch, and means coacting with both said interlock and latch for permitting the use of either the interlock or the latch, or both.

45. In combination with a switch box having a cover thereon and switch operating mechanism therein, an interlocking mechanism whereby the cover cannot be opened while the switch is closed nor the switch closed while the cover is open, a cover latch, and a member operable to disable said interlocking mechanism by interfitting connection with portions of the latter, said member being also used for locking said cover latch to hold said cover closed.

46. In combination with a switch box having a cover thereon and switch operating mechanism therein, an interlocking mechanism whereby the cover cannot be opened while the switch is closed nor the switch closed while the cover is open, a cover latch, and means comprising locking members and a key operating the same for locking said cover latch to hold said cover closed, said key also cooperating with the interlocking mechanism to nullify the interlock when desired.

47. In combination with a switch box having a cover thereon and switch operating mechanism therein, an interlocking mechanism whereby the cover cannot be opened while the switch is closed nor the switch closed while the cover is open, a cover latch, means comprising locking members and a key operating the same for locking said cover latch to hold said cover closed, said key also cooperating with the interlocking mechanism to nullify the interlock when desired, and means for preventing an inadvertent locking of the latch.

48. In combination with a switch box having a cover thereon and switch operating mechanism therein, an interlocking mechanism whereby the cover cannot be opened while the switch is closed nor the switch closed while the cover is open, a cover latch, means for locking said cover latch to hold said cover closed, and means preventing the inadvertent movement of said last named means to lock the latch.

49. In combination with a switch box having a cover thereon and switch operating mechanism therein, an interlocking mechanism whereby the cover cannot be opened while the switch is closed nor the switch closed while the cover is open, a cover latch,

- association with said interlock, and a cover latch positioned within said housing and projecting therefrom, said housing being removable from, and connectible to, said switch box 5 as a unit, and being capable of direct association with the normal switch operating mechanism in said box whereby the character of said switch may be readily altered.
60. In combination with a switch box having a cover thereon and switch operating mechanism therein, an interlocking mechanism whereby the cover cannot be opened while the switch is closed nor the switch closed while the cover is open, a housing within 10 which said mechanism is positioned and into which a portion of said normal switch operating means may be projected for operative association with said interlock and also into which a portion of said cover may project 15 for association with said interlock, and a cover latch positioned within said housing and projecting therefrom, interlock and latch controlling means, said housing and said box having registering openings to permit the entrance of said controlling means from the outside of said box.
61. In combination with a switch box having a cover thereon and a switch operating mechanism therein, an engageable member on 20 said cover, an interlocking mechanism removable as a unit from said box comprising a cover locking member, a switch locking member, said members being pivotally mounted on a common support, means comprising a 25 spring attached to said support and having two arms, one engaging each member, for normally urging said members into locking position, each of said members being provided with a hooked portion to engage selected elements, and means for moving said switch locking member into unlocking position as the cover is closed.
62. In combination with a switch box having a cover thereon and a switch operating 30 mechanism therein, an engageable hasp on said cover, an interlocking mechanism comprising a cover locking member, a switch locking member, means for normally urging said members into locking position, each of 35 said members being provided with a hooked portion to engage selected elements, means for moving said switch locking member into unlocking position as the cover is closed, and means comprising a key member insertible 40 into operative association with the interlock from the exterior of said box for moving said cover locking member from engagement with said hasp although the switch is closed and for moving said switch locking member out 45 of engagement with said switch operating means although said cover is open, said key comprising ward portions which severally engage said locking members to move them from their locking positions.
63. In combination with a switch box hav- 50 ing a cover thereon and a switch operating mechanism therein, an engageable hasp on said cover, an interlocking mechanism comprising a cover locking member, a switch locking member, means for normally urging 55 said members into locking position, each of said members being provided with a hooked portion to engage selected elements, means for moving said switch locking member into unlocking position as the cover is closed, and means comprising a key member insertible 60 into operative association with the interlock from the exterior of said box for moving said cover locking member from engagement with said hasp although the switch is closed and for moving said switch locking member out 65 of engagement with said switch operating means although said cover is open, said key comprising ward portions which severally engage said locking members to move them from their locking positions.
64. In combination with a switch box having a cover thereon and a switch operating mechanism therein, an engageable member on said cover, interlocking mechanism comprising a cover locking member cooperating with said engageable member, a switch locking member for preventing movement of said switch operating means, said members being normally urged towards locking position, a latch adapted to normally engage said cover but being yieldable to allow said cover to open and close, said latch being associated with said interlocking mechanism, and means comprising a key for locking said latch, when desired.
65. In a switch box having a cover thereon and a switch operating mechanism therein, an engageable member on said cover, interlocking mechanism comprising a cover locking member cooperating with said engageable member, a switch locking member for preventing movement of said switch operating means, said members being normally urged towards locking position, a latch adapted to normally engage said cover but being yieldable to allow said cover to open and close, said latch being associated with said interlocking mechanism, and means comprising a key for locking said latch or for disabling said locking members.
66. In a switch box having a cover thereon and a switch operating mechanism therein, an engageable member on said cover, an interlocking mechanism comprising a cover locking member cooperating with said engageable member, a switch locking member for preventing movement of said switch operating means, said members being normally urged towards locking position, a latch adapted to normally engage said cover but being yieldable to allow said cover to open and close, said latch being associated with

said interlocking mechanism, and means comprising a key having wards for locking said latch or for disabling said locking members, the wards of said key being so positioned that 5 movement of the key in one direction locks said latch whereas movement in the other direction disables said interlock.

67. In a switch box having a cover thereon and a switch operating mechanism therein, 10 an engageable member on said cover, an interlocking mechanism comprising a cover locking member cooperating with said engageable member, a switch locking member for preventing movement of said switch operating means, said members being normally urged towards locking position, a latch adapted to normally engage said cover but being yieldable to allow said cover to open and close, said latch being associated with 15 said interlocking mechanism, means comprising a key and a key supporting member for locking said latch, or for disabling said locking members, and a locking disc mounted on said key supporting member adapted, when 20 moved in one direction, to engage and lock said latch to keep said cover closed.

68. In a switch box having a cover thereon and a switch operating mechanism therein, an engageable member on said cover, an interlocking mechanism comprising a cover locking member cooperating with said engageable member, a switch locking member for preventing movement of said switch operating means, said members being normally urged 30 towards locking position, a latch adapted to normally engage said cover but being yieldable to allow said cover to open and close, said latch being associated with said interlocking mechanism, means comprising a key and a key supporting member for locking said latch or for disabling said interlocking members, a locking disc mounted on said key supporting member adapted, when 35 moved in one direction, to engage and lock said latch to keep said cover closed, and means to prevent the inadvertent movement of said key to lock said latch.

69. In a switch box having a cover thereon and a switch operating mechanism therein, an engageable member on said cover, an interlocking mechanism comprising a cover locking member cooperating with said engageable member, a switch locking member for preventing movement of said switch operating 50 means, said members being normally urged towards locking position, a latch adapted to normally engage said cover but being yieldable to allow said cover to open and close, said latch being associated with said interlocking mechanism, means comprising a key and a key supporting member for locking said latch or for disabling said locking members, a locking disc mounted on said key supporting member adapted, when 55 moved in one direction, to engage and lock

said latch to keep said cover closed, and means comprising a member obstructing the movement of said disc to prevent the inadvertent movement of said key to lock said latch. 70

70. In a switch box having a cover thereon and a switch operating mechanism therein, an engageable member on said cover, an interlocking mechanism comprising a cover locking member cooperating with said engageable member, a switch locking member for preventing movement of said switch operating means, said members being normally urged towards locking position, a latch adapted to normally engage said cover but being yieldable to allow said cover to open and close, said latch being associated with said interlocking mechanism, means comprising a key and a key supporting member for locking said latch or for disabling said locking members, a locking disc mounted on said key supporting member adapted, when moved in one direction, to engage and lock said latch to keep said cover closed, means comprising a member obstructing the movement of said disc to prevent the inadvertent movement of said key to lock said latch, and means accessible from the exterior of said switch box to remove said obstruction when the operator intends to lock said cover shut 80 with said latch.

71. In a switch box having a cover thereon and a switch operating mechanism therein, an engageable member on said cover, an interlocking mechanism comprising a cover locking member cooperating with said engageable member, a switch locking member for preventing movement of said switch operating means, said members being normally urged towards locking position, a latch adapted to normally engage said cover but being yieldable to allow said cover to open and close, said latch being associated with said interlocking mechanism, means comprising a key and a key supporting member for locking said latch or for disabling said locking members, a locking disc mounted on said key supporting member adapted, when moved in one direction, to engage and lock said latch to keep said cover closed, means comprising a key and a key supporting member for locking said latch or for disabling said locking members, a locking disc mounted on said key supporting member adapted, when moved in one direction, to engage and lock said latch to keep said cover closed, means comprising a spring member obstructing the movement of said disc to prevent the inadvertent movement of said key to lock said latch, and means comprising a push button member accessible from the exterior of said switch box to remove said obstruction when the operator intends to lock said cover shut with said latch. 100

72. In a switch box having a cover thereon and a switch operating mechanism therein, an engageable member on said cover, an interlocking mechanism comprising a cover locking member cooperating with said engageable member, a switch locking member for preventing movement of said switch operating 110 means, said members being normally urged towards locking position, a latch adapted to normally engage said cover but being yieldable to allow said cover to open and close, said latch being associated with said interlocking mechanism, means comprising a key and a key supporting member for locking said latch or for disabling said locking members, a locking disc mounted on said key supporting member adapted, when moved in one direction, to engage and lock said latch to keep said cover closed, means comprising a spring member obstructing the movement of said disc to prevent the inadvertent movement of said key to lock said latch, and means comprising a push button member accessible from the exterior of said switch box to remove said obstruction when the operator intends to lock said cover shut with said latch. 120

73. In a switch box having a cover thereon and a switch operating mechanism therein, an engageable member on said cover, an interlocking mechanism comprising a cover locking member cooperating with said engageable member, a switch locking member for preventing movement of said switch operating 130 means, said members being normally urged towards locking position, a latch adapted to normally engage said cover but being yieldable to allow said cover to open and close, said latch being associated with said interlocking mechanism, means comprising a key and a key supporting member for locking said latch or for disabling said locking members, a locking disc mounted on said key supporting member adapted, when moved in one direction, to engage and lock

means, said members being normally urged towards locking position, a latch adapted to normally engage said cover but being yieldable to allow said cover to open and close, 5 said latch being associated with said interlocking mechanism, means comprising a key and a key supporting member for locking said latch or for disabling said locking members, a locking disc mounted on said key supporting member adapted, when moved in one direction, to engage and lock said latch to keep said cover closed, means comprising a spring member obstructing the movement of said disc to prevent the inadvertent movement 10 of said key to lock said latch, means comprising a push button member accessible from the exterior of said switch box to remove said obstruction when the operator intends to lock said cover shut with said latch, and means 15 for holding said disc in locking position until positively unlocked by said key.

73. In a switch box having a cover thereon and a switch operating mechanism therein, an engageable member on said cover, an interlocking mechanism comprising a cover locking member cooperating with said engageable member, a switch locking member for preventing movement of said switch operating means, said members being normally urged towards locking position, a latch adapted to normally engage said cover but being yieldable to allow said cover to open and close, said latch being associated with said interlocking mechanism, means comprising 25 a key and a key supporting member for locking said latch or for disabling said locking members, a locking disc mounted on said key supporting member adapted, when moved in one direction, to engage and lock said latch 30 to keep said cover closed, means comprising a spring member obstructing the movement of said disc to prevent the inadvertent movement of said key to lock said latch, means comprising a push button member accessible 35 from the exterior of said switch box to remove said obstruction when the operator intends to lock said cover shut with said latch, and a housing for all of said mechanism having a keyhole therein, and having apertures to permit the entrance of the switch operating means and said cover member, and said latch protruding from said housing whereby the entire mechanism is removable as a unit from 40 said box.

55 74. In a switch box having a cover thereon and a switch operating mechanism therein, a movable rod associated with said mechanism, a unitary interlocking mechanism capable of ready association with said rod where- 60 by no substantial alteration is necessitated in changing from a non-interlocked switch to an interlocked one and vice versa.

75. In a switch box having a cover thereon and a switch operating mechanism therein, 65 the latter comprising a movable rod having

the end thereof elbowed, a unitary interlocking mechanism capable of ready association with said rod and the elements of said mechanism being formed to cooperate with said elbowed end whereby no substantial alteration is necessitated in changing from a non-interlocked switch to an interlocked one and vice versa. 70

76. In combination with a switch box having a cover thereon and switch operating mechanism therein, an interlocking mechanism whereby the cover cannot be opened while the switch is closed nor the switch closed while the cover is open, means for disabling the interlocking mechanism comprising a key, and a cover latch operated by turning said key in a direction reversely to that in which the key is turned to disable said interlocking mechanism. 75

77. In combination with a switch box having a cover thereon and switch operating mechanism therein, an interlocking mechanism whereby the cover cannot be opened while the switch is closed nor the switch closed while the cover is open, means for disabling the interlocking mechanism comprising a key, a spring cover latch for locking the cover permanently closed, a key cylinder upon which said latch is mounted, said cover latch being operated by the key by turning it 80 in a direction reversely to that required to disable the interlocking mechanism. 90

In witness whereof, I have hereunto subscribed my name.

PAUL S. JENKINS. 100
